DESIGN FOR A DISPENSING BOOTH OR SIMILAR ARTICLE

Ralph H. Ward, Chicago, Ill., assignor to B/G
Foods, Inc., Chicago, Ill., a corporation of Dela-
ware

Application August 19, 1935, Serial No. 58,197

Term of patent 7 years

To all whom it may concern:

Be it known that I, Ralph H. Ward, a citizen
of the United States of America, residing at Chi-
cago, in the county of Cook and State of Illinois,
have invented a new, original, and ornamental
Design for a Dispensing Booth or Similar Article,
of which the following is a specification, refer-
ence being had to the accompanying drawing,
forming a part thereof.

In the drawing:

Fig. 1 is a perspective view of a dispensing
booth showing my new design.

Fig. 2 is a vertical front elevation.

Fig. 3 is a vertical side elevation.

Fig. 4 is a plan view of the booth.

I claim:

The ornamental design for a dispensing booth
or similar article, substantially as shown.

Signed at Chicago, Cook County, Illinois, this
17th day of August, 1935.

RALPH H. WARD.
